INTERMITTENT FILM FEED

Paul Georges Cazes, Paris, France, assignor to
 Pathé Cinéma Anciens Etablissements Pathé
 Frères, Paris, France

Application January 11, 1938, Serial No. 184,387
 In France April 1, 1937

1 Claim. (Cl. 88—18.4)

It is shown by experience that in cinematographic apparatus in which the film is fed by a claw carrying member actuated by a cam, the wear of the parts in contact has a marked effect 5 upon the fixed position of the projection and also upon the noise resulting from the operation.

The present invention has for its object to improve the film operating devices of the aforesaid type by removing all the disadvantages due 10 to the wear of the parts and it primarily consists in providing elastic means whereby the claw carrying slide is yieldingly pressed into contact with its operating and supporting members.

Other characteristic features of the invention 15 will be hereinafter set forth.

The accompanying drawing, which is given solely by way of example, represents an improved feeding mechanism in accordance with the invention.

20 In the embodiment herein represented, the slide 1 carrying the claws 2 at its front end is provided with a peripheral ridge 1^a which is acted upon by a cam 3 carried by a shaft 4 rotating in stationary bearings. The cam 3 is provided with a crank 25 pin 5 extending into an oblique slot 12 of the slide. The said slide is provided at the rear end with a tail 6 having a slot 6^a into which extends a pivot or supporting pin 7 which is stationary but adjustable in position.

30 The tail 6 of slide 1 has a lug 8 pierced with a hole 9 for attaching a spring 10 held at its opposite end by a stud 11 secured to the frame of the apparatus. Said spring has a portion slightly inclined on the horizontal and in the example 35 shown, its attaching point 9 is so arranged that it lies always at the right of the supporting pin 7.

The operation is as follows: when the cam 3 is rotated in the direction of arrow f¹, the slide is 40 imparted a vertical reciprocating movement as shown by arrow f¹ combined with a horizontal reciprocating movement as shown by arrow f², whereby the desired feeding motion is imparted to the claws 2.

On the other hand, due to the spring 10, the 45 slide is subjected to a horizontal force to the left according to the arrow f⁴, whereby the edge ab of the oblique slot 12 in the said slide is constantly pressed against the crank pin 5. Any lost motion is thus prevented in the horizontal

direction between the slide and the crank pin. At the same time, the right hand end of the slide is subjected by the spring 10 to a downward force according to the arrow f³, adapted to press the upper edge cd of the slot 6^a against the supporting stud 7, and said stud 7 acting as a fulcrum for the slide, the lower part of the ridge 1^a on the slide will be held permanently in contact at e with the cam 3, whereby any lost motion between the slide and the cam in the vertical direction is avoided.

As results from the above, the left hand part of the slide is urged upwardly and to the left by the action of spring 10 and it is urged downwardly and to the right by the cam and the crank pin 15 respectively.

Obviously the invention is not limited to the embodiment herein described and represented, which is given solely by way of example.

Having now described my invention what I 20 claim as new and desire to secure by Letters Patent is:

In a cinematograph apparatus, in combination with a stationary pivot, a slide provided on one lateral side with at least one claw, on the opposite lateral side with a guiding slot substantially at right angles with said lateral sides and engaging slidably and pivotally said pivot, and between said claw and said guiding slot with a bearing surface facing upwards and substantially parallel 30 to said guiding slot and with an oblique surface facing said claw and having its lower end nearer said guiding slot than its upper end, a cam engaging said bearing surface and adapted to impart to said slide downward movements, controlling means engaging said oblique surface and adapted to impart to said slide lateral movements towards said pivot, stationary attaching means situated below said slide, and a spring attached at one end to said attaching means and at its 40 other end to said slide at a point situated below said pivot and above said attaching means and adapted to urge constantly and simultaneously the upper side of said guiding slot against said pivot, said bearing surface against said cam and 45 said oblique surface against said controlling means.

PAUL GEORGES CAZES.
